UNITED STATES PATENT OFFICE.

JOSEPH C. GENTRY, OF AMERICUS, MISSOURI.

LID-FASTENER FOR SHIPPING-CRATES, &c.

SPECIFICATION forming part of Letters Patent No. 690,266, dated December 31, 1901.

Application filed August 23, 1900. Serial No. 27,814. (No model.)

To all whom it may concern:

Be it known that I, JOSEPH C. GENTRY, a citizen of the United States, residing at Americus, in the county of Montgomery and State 5 of Missouri, have invented certain new and useful Improvements in Lid-Fasteners for Shipping-Crates, &c.; and I do hereby declare the following to be a full, clear, and exact description of the invention, such as 10 will enable others skilled in the art to which it appertains to make and use the same.

My invention relates to fasteners for the lids of shipping-crates and the like; and the objects and advantages will be made fully 15 apparent from the following specification considered in connection with the accompanying drawings, in which—

Figure 1 is a top plan view of a shipping-crater with my lid-fastener applied and showing the top section or lid thereof removed. Fig. 2 is a vertical-central section of a shipping-crater with my improved lid-fastener applied and complete ready for use.

In order to conveniently refer to the several features of my invention and their coöperating accessories, numerals will be employed, of which 1 designates the crate.

2 is the lid or cover, having the downwardly-extending flanges 3 of sufficient length to permit the flanges 3 to receive or telescope with the body of the crate, and in order to hold the lid in place I provide the depending hooks 4, which consist of a suitable piece of spring metal properly secured to the lid in any preferred way and depending into engagement with the toothed spring-bar 5, attached within the recess 6, provided in each of the end sections. The lower end of the spring-bar 5 is properly corrugated or provided with the teeth or ratchets 7 and also with the operating-handle 8, and since the recess 6 is of proper depth to freely receive the lower corrugated end of the spring-bar 5 and since

said bar is formed of suitable spring metal the said teeth or corrugations may be forced inward by pressure upon the handle 8, and thus moved out of engagement with the hook 4 when it is desired to release said hook. By providing the spring-bars 5 with a series of teeth the lid may be held in different positions as regards the crate, as circumstances may require. By thus disposing the teeth or corrugations within the recess 6 they are protected against casual displacement or injury, and sufficient room is also provided to enable 55 said parts to be moved inward out of engagement with the hooks, thereby permitting said hooks to be formed of heavier or stronger portions of metal.

Having thus fully described my invention, 60 what I claim as new, and desire to secure by Letters Patent, is—

In a shipping-crater, a cover provided with end flanges and depending hooks having inwardly-extending free ends, the crate having 65 its ends provided with recesses upon their outer faces and spring-bars secured at one end within said recesses with their lower ends free and provided with a series of teeth and the extreme end bent outwardly to form an 70 operating-handle, said spring-bars normally extended outwardly whereby their teeth are engaged by the inwardly-extended free ends of the hooks and the recesses being of sufficient depth to allow of the inward movement 75 of the lower ends of the spring-bars to permit of the disengagement of the hooks therefrom and the removal of the cover, substantially as described.

In testimony whereof I affix my signature 80 in presence of two witnesses.

JOSEPH C. GENTRY.
